CEILING SUSPENDED, ELEVATABLE TABLE

Opha F. Blumer, Moravia, Iowa

Application August 26, 1946, Serial No. 693,122

2 Claims. (Cl. 311—17)

1

This invention relates generally to furniture and pertains more particularly to the class of tables.

It has been the experience of everyone at some time or other to have to straddle a dining-table leg particularly when it becomes necessary to seat about a dining table or other table, a greater number of persons than the table was designed to accommodate.

In the light of the foregoing it is an object of the present invention to provide a table of novel design which is entirely free of legs or other underlying support, whereby persons can be seated at any position around such table without the annoyance of having to straddle a supporting leg.

Another object of the invention is to provide a table of the character stated, which is provided with a central vertically extending suspension means, designed to be attached to the ceiling of the room in which the table is used and to be raised to a position closely adjacent to such ceiling, when not in use.

Still another object of the invention is to provide a suspended table structure wherein the suspension means is of telescoping form and designed to extend through the ceiling of the room in which the table is used, so that the table when not in use may be raised to a position closely adjacent to such ceiling thereby providing additional room space.

Other objects and advantages of the invention will become apparent as the description of the same proceeds and the invention will be best understood from a consideration of the following detailed description taken in connection with the accompanying drawings forming a part of the specification with the understanding, however, that the invention is not confined to a strict conformity with the showing of the drawings but may be changed or modified so long as such changes or modifications mark no material departure from the salient features of the invention as expressed in the appended claims.

In the drawings:

Figure 1 is a vertical section through a building and a room thereof showing a table structure installed therein, in accordance with the present invention, portions of the structure being in section.

Figure 2 is a vertical longitudinal section through the table supporting mechanism, showing the parts extended, the same being on an enlarged scale.

Figure 3 is a vertical longitudinal section, on

an enlarged scale through the table suspension mechanism, showing the same retracted.

Figure 4 is a horizontal section taken substantially on the line 4—4 of Figure 3.

Referring now more particularly to the drawings the numeral 10 generally designates a building structure in which is shown a room 11 in which a table constructed in accordance with the present invention is shown installed.

It will be understood, of course, that this illustration of a single room building is made merely for the purpose of illustrating in the most convenient manner the way in which a table constricted in accordance with the present invention may be installed.

In the installation of the present invention the ceiling 12 of the room in which the table is to be used, is provided with an opening 13 which is bounded by the annulus 14, secured to the ceiling in a suitable manner as, for example, by the use of screws 15. This annulus 14 has the inwardly directed flange 16 which functions, in the manner hereinafter described, as a stop for the body of the table when the latter is drawn upwardly into an operative position.

Mounted above the ceiling opening 13, upon a suitable support such, for example, as the ceiling joists 17, is a stop plate 18, which is secured in position in any suitable manner as, for example, by the use of screws 19. This stop plate 18 has an opening 18a which is of substantially the same inside diameter as the flange 16 and is concentric therewith and in addition it is provided, at two or more points with apertures 20 for the purpose hereinafter described.

The numeral 21 generally designates a telescoping hanger or support for the table 22. This hanger 21 is here shown as comprising the two cylinders 23 and 24. While only two units are shown as making up the hanger 21, it will be readily apparent that more may be used if found advisable.

The lower cylinder 23 has a closure plate 25 in the bottom or lower end thereof and this is secured by securing elements 26 to the table 22 as shown.

The upper end of the cylinder 23 carries the vertically spaced concentric inner and outer collars 27 and 28 respectively. The inner one of these collars has two or more apertures 29 therethrough for the purpose hereinafter stated.

The smaller cylinder 24 is slidably extended through the collars 27 and 28 and is fitted snugly thereto. At its lower end and within the cylinder 23, the cylinder 24 has the outwardly directed en-

circling flange 30 which when the supported structure 21 is extended, comes to rest against the under side of the inner collar 27 as shown in Figure 2. This flange carries a number of up-standing pins 31 which are designed to enter the openings 29 so as to couple the cylinders together against relative turning movement.

The overall diameter of the lower and larger cylinder 23 is only slightly less than the inside diameter of the flange 16 and ring 18 so that when the suspending structure is drawn up or collapsed it extends snugly through these parts as shown in Figure 3.

At its upper end the smaller cylinder 24 has connected thereto the integral head plate 32 which is of a diameter greater than the inside diameter of the ring 18 through which the small cylinder 24 extends so that when the cylinders are extended for the purpose of suspending the table at the proper elevation above the floor 33 of the room, for use, the head plate will come to rest upon the top of the ring 18 as shown in Figure 2.

The head plate 32 carries pins 34, equal in number to the apertures 20 in the plate 18, which are designed to enter the apertures 20 in the plate 18 when the support is extended, so as to hold the entire supporting structure against turning movement.

While any suitable means may be employed for telescoping the table supporting structure 21 for the purpose of raising the table there is here shown a lifting cable 35 which extends through the tubes as shown and is attached at one end, as at 36, to the table 22 and to the end plate 25 of the cylinder 23. This cable is passed upwardly into the area above the room ceiling 12 and over a suitable guide pulley 37 from which it is carried in a suitable manner as, for example, across the pulley 38, back down into the room 11 or into any other desired room where it is attached to a winding mechanism, generally designated 39. This mechanism is here shown as comprising a drum 40 having an operating crank 41 whereby it may be turned to wind up the cable 35 for lifting the table. A suitable housing 42 may be provided to enclose the drum 40.

From the foregoing it will be readily apparent that there is provided in the present invention a novel table structure which when lowered to the full extent of the supporting means 21 may be maintained at the proper elevation above the floor 33 and used without the usual annoyance of having legs interfering with the proper positioning of persons around the table. When the table is fully lowered the pins 31 engage in the apertures 29 and the pins 34 engage in the apertures 20 so that the entire structure is held against rotation.

When the table is drawn up to the position shown in Figure 3 the larger cylinder will extend through the opening of the plate 18 and through the flange 16 of the annulus 14 and the top of the table will come to rest against the under side of the flange thus effectively closing the opening 13 in the ceiling.

If desired, suitable felt material may be placed inside the annulus 14 to wipe the surface of the cylinder 23 and the space between the inner and outer collars 27 and 28 may be utilized in the

same manner to wipe the surface of the cylinder 24. In this manner the cylinders may be kept clean and polished and also, when the table is raised and out of use, such material within the annulus 14 will prevent the passage of dust through the opening 13 downwardly into the room.

I claim:

- 10 1. A table structure for use in a room having a ceiling provided with an opening, comprising a table body, a supporting unit consisting of two telescopically connected cylinders, one of the cylinders being secured at one end to the center of the table body, the other cylinder at its outer end having an integral head plate, a supporting plate having a central opening through which the said other cylinder passes, means mounting said supporting plate above the room ceiling with the opening of the supporting plate concentric with said ceiling opening, the head plate normally resting upon the supporting plate, means for telescoping said cylinders and elevating the same through the ceiling opening and through the supporting plate opening to position the table body adjacent to the ceiling and the telescoped cylinders substantially entirely above the ceiling, means for locking the head plate and supporting plate together against relative turning, which becomes effective when the supporting unit is in extended table supporting position, and means for locking the cylinders together against relative turning movement, which becomes effective when the unit is in the said extended table supporting position.
- 15 2. A table structure for use in a room having a ceiling provided with an opening, comprising a table body, a supporting unit consisting of two telescopically connected cylinders, one of the cylinders being secured at one end to the center of the table body, the other cylinder at its outer end having an integral head plate, a supporting plate having a central opening through which the said other cylinder passes, means mounting said supporting plate above the room ceiling with the opening of the supporting plate concentric with said ceiling opening, the head plate normally resting upon the supporting plate, means for telescoping said cylinders and elevating the same through the ceiling opening and through the supporting plate opening to position the table body adjacent to the ceiling and the telescoped cylinders substantially entirely above the ceiling, and a stop collar encircling said ceiling opening and disposed upon the underside of the ceiling to be engaged by the table body when the latter is at its maximum elevated position.
- 20 3. A table structure for use in a room having a ceiling provided with an opening, comprising a table body, a supporting unit consisting of two telescopically connected cylinders, one of the cylinders being secured at one end to the center of the table body, the other cylinder at its outer end having an integral head plate, a supporting plate having a central opening through which the said other cylinder passes, means mounting said supporting plate above the room ceiling with the opening of the supporting plate concentric with said ceiling opening, the head plate normally resting upon the supporting plate, means for telescoping said cylinders and elevating the same through the ceiling opening and through the supporting plate opening to position the table body adjacent to the ceiling and the telescoped cylinders substantially entirely above the ceiling, and a stop collar encircling said ceiling opening and disposed upon the underside of the ceiling to be engaged by the table body when the latter is at its maximum elevated position.
- 25 4. A table structure for use in a room having a ceiling provided with an opening, comprising a table body, a supporting unit consisting of two telescopically connected cylinders, one of the cylinders being secured at one end to the center of the table body, the other cylinder at its outer end having an integral head plate, a supporting plate having a central opening through which the said other cylinder passes, means mounting said supporting plate above the room ceiling with the opening of the supporting plate concentric with said ceiling opening, the head plate normally resting upon the supporting plate, means for telescoping said cylinders and elevating the same through the ceiling opening and through the supporting plate opening to position the table body adjacent to the ceiling and the telescoped cylinders substantially entirely above the ceiling, and a stop collar encircling said ceiling opening and disposed upon the underside of the ceiling to be engaged by the table body when the latter is at its maximum elevated position.
- 30 5. A table structure for use in a room having a ceiling provided with an opening, comprising a table body, a supporting unit consisting of two telescopically connected cylinders, one of the cylinders being secured at one end to the center of the table body, the other cylinder at its outer end having an integral head plate, a supporting plate having a central opening through which the said other cylinder passes, means mounting said supporting plate above the room ceiling with the opening of the supporting plate concentric with said ceiling opening, the head plate normally resting upon the supporting plate, means for telescoping said cylinders and elevating the same through the ceiling opening and through the supporting plate opening to position the table body adjacent to the ceiling and the telescoped cylinders substantially entirely above the ceiling, and a stop collar encircling said ceiling opening and disposed upon the underside of the ceiling to be engaged by the table body when the latter is at its maximum elevated position.
- 35 6. A table structure for use in a room having a ceiling provided with an opening, comprising a table body, a supporting unit consisting of two telescopically connected cylinders, one of the cylinders being secured at one end to the center of the table body, the other cylinder at its outer end having an integral head plate, a supporting plate having a central opening through which the said other cylinder passes, means mounting said supporting plate above the room ceiling with the opening of the supporting plate concentric with said ceiling opening, the head plate normally resting upon the supporting plate, means for telescoping said cylinders and elevating the same through the ceiling opening and through the supporting plate opening to position the table body adjacent to the ceiling and the telescoped cylinders substantially entirely above the ceiling, and a stop collar encircling said ceiling opening and disposed upon the underside of the ceiling to be engaged by the table body when the latter is at its maximum elevated position.
- 40 7. A table structure for use in a room having a ceiling provided with an opening, comprising a table body, a supporting unit consisting of two telescopically connected cylinders, one of the cylinders being secured at one end to the center of the table body, the other cylinder at its outer end having an integral head plate, a supporting plate having a central opening through which the said other cylinder passes, means mounting said supporting plate above the room ceiling with the opening of the supporting plate concentric with said ceiling opening, the head plate normally resting upon the supporting plate, means for telescoping said cylinders and elevating the same through the ceiling opening and through the supporting plate opening to position the table body adjacent to the ceiling and the telescoped cylinders substantially entirely above the ceiling, and a stop collar encircling said ceiling opening and disposed upon the underside of the ceiling to be engaged by the table body when the latter is at its maximum elevated position.
- 45 8. A table structure for use in a room having a ceiling provided with an opening, comprising a table body, a supporting unit consisting of two telescopically connected cylinders, one of the cylinders being secured at one end to the center of the table body, the other cylinder at its outer end having an integral head plate, a supporting plate having a central opening through which the said other cylinder passes, means mounting said supporting plate above the room ceiling with the opening of the supporting plate concentric with said ceiling opening, the head plate normally resting upon the supporting plate, means for telescoping said cylinders and elevating the same through the ceiling opening and through the supporting plate opening to position the table body adjacent to the ceiling and the telescoped cylinders substantially entirely above the ceiling, and a stop collar encircling said ceiling opening and disposed upon the underside of the ceiling to be engaged by the table body when the latter is at its maximum elevated position.
- 50 9. A table structure for use in a room having a ceiling provided with an opening, comprising a table body, a supporting unit consisting of two telescopically connected cylinders, one of the cylinders being secured at one end to the center of the table body, the other cylinder at its outer end having an integral head plate, a supporting plate having a central opening through which the said other cylinder passes, means mounting said supporting plate above the room ceiling with the opening of the supporting plate concentric with said ceiling opening, the head plate normally resting upon the supporting plate, means for telescoping said cylinders and elevating the same through the ceiling opening and through the supporting plate opening to position the table body adjacent to the ceiling and the telescoped cylinders substantially entirely above the ceiling, and a stop collar encircling said ceiling opening and disposed upon the underside of the ceiling to be engaged by the table body when the latter is at its maximum elevated position.
- 55 10. A table structure for use in a room having a ceiling provided with an opening, comprising a table body, a supporting unit consisting of two telescopically connected cylinders, one of the cylinders being secured at one end to the center of the table body, the other cylinder at its outer end having an integral head plate, a supporting plate having a central opening through which the said other cylinder passes, means mounting said supporting plate above the room ceiling with the opening of the supporting plate concentric with said ceiling opening, the head plate normally resting upon the supporting plate, means for telescoping said cylinders and elevating the same through the ceiling opening and through the supporting plate opening to position the table body adjacent to the ceiling and the telescoped cylinders substantially entirely above the ceiling, and a stop collar encircling said ceiling opening and disposed upon the underside of the ceiling to be engaged by the table body when the latter is at its maximum elevated position.
